Inventor
George B. Holzach

United States Patent Office.

GEORGE B. HOLZACH, OF NEW ORLEANS, LOUISIANA.

Letters Patent No. 95,349, dated September 28, 1869.

IMPROVED WINDOW-SHADE FIXTURE.

The Schedule referred to in these Letters Patent and making part of the same.

To all whom it may concern:

Be it known that I, GEORGE B. HOLZACH, of the city of New Orleans, parish of Orleans, and State of Louisiana, have invented a certain new, useful, and improved Mode of Hanging and Operating Window-Shades; and I do hereby declare the following to be a full, clear, and exact description of the same, reference being had to the annexed drawing, making a part of this specification.

The object of my invention is to provide a means of hanging the shades of windows in such manner, that the point at which they are rolled up may be changed at pleasure, and thus either half of the window, or any section of either half, or of the whole window, be covered or screened by the shade, accordingly as the convenience of the inmates of the room or house into which the window looks, may make it desirable.

My invention consists of a transverse-sliding bar, that is so adjusted within the frame of the window, as to be readily moved up and down therein, by proper appliances, upon which is secured an ordinary roller, to which the shade is attached in any ordinary manner.

But my invention will be better understood by reference to the drawing, which clearly indicates its nature.

On the drawing—

A represents a window-frame, across which is fitted and placed, a sliding bar, B, that, through the agency of properly-formed extremities and grooves or rebates, or some other equivalent arrangement in the two sides of the window-frame, is readily movable, whilst preserving a horizontal or level position, from the top to the bottom of the window, and *vice versa*.

Any proper mechanical arrangement which will allow the bar B to be moved and adjusted to any point between the two extremities of the window would be regarded by me as an equivalent of that shown on the drawings, and equally open to be used by me.

To the bar B, by means of brackets *a a'*, a shade-roller, C, is secured, and to this roller a shade, D, is fastened at its upper end, by any usual means.

Two cords, *b c*, afford the means for raising, lowering, and holding the bar B to and in any desired position, for, as an inspection of the drawing will show, they are connected at one end to the said bar, either by being tied around the brackets *a a'*, as shown, or by being secured directly to the bar itself, by any proper means, and pass over grooved pulleys at the top of the window, as shown at *d e*.

These cords are to be adjusted so as to hold the bar horizontally, and a weight, E, being fastened to them,

as shown, which just balances the weight of the bar and its attachments, it is easy to perceive that said bar can be readily moved up or down by pulling down or lifting up said weight, and also that it will remain wherever placed, by the counterbalance of the weight E.

The cords *d e* may be exposed, as shown, or, with the pulleys on which they operate, they may be hidden in properly-formed recesses in the window-frame.

An endless cord, *f*, which passes over or around groove-pulleys *g h*, placed respectively at the top and bottom of the frame A, and encircling, by one or two turns, a pulley, *i*, on the roller C, operates the shade D, and regulates its fall conformably to the position of the bar B with relation to the top and bottom of the window.

The drawing shows the bar B at or near the centre of the frame A, and in proper position, therefore, to unscreen the upper half of the window. A further depression would obviously enlarge the unshaded space in the same upper section of the window, whilst by elevating it to the top of the frame, and rolling up the shade, any portion of the window, beginning from the bottom, will be unscreened.

It will be further observed, that my invention provides for covering with the shade, any part of the window, from top to bottom, by a wider or narrower cross-screen, as may be desired, and that in whatever position the bar B be placed, the whole of the shade may be rolled up, and the whole window unscreened.

It will be observed that I employ no spring whatever in connection with my improvement.

One among many advantages resulting from my invention is that it allows the upper sash of a window to be opened for purposes of ventilation without taking off the shade from the lower part, and thus screens the inmates of a house from observation, whilst giving them the full benefit of fresh air.

Having thus described my invention,

What I claim, and desire to secure by Letters Patent, is—

The means herein described, consisting of an endless cord, *f*, in connection with its attachment to the roller C and the cord *b c*, and its connection with the cross-bar B, for winding and unwinding the shade upon its roller, simultaneously with the raising and lowering of the supporting and carrying-bar, substantially as before described.

GEORGE B. HOLZACH.
